UNITED STATES PATENT OFFICE.

WILLIAM E. BARTON, OF EAST HAMPTON, CONNECTICUT.

DESIGN FOR SLEIGH-BELL STRAP.

Specification forming part of Design No. 7,234, dated March 10, 1874; application filed December 10, 1873
 [Term of Patent 14 years.]

To all whom it may concern:

Be it known that I, WILLIAM E. BARTON, of East Hampton, in the county of Windham and State of Connecticut, have invented a new Design for Sleigh-Bell Strap; and I do hereby declare the following, when taken in connection with the accompanying drawing and the letters of reference marked thereon, to be a full, clear, and exact description of the same, and which said drawing constitutes part of this specification, and represents a front view.

This invention relates to a design for a bell-strap, such as are used upon horses in sleighing, commonly called sleigh-bells; and consists in the peculiar configuration of the strap, with bells arranged thereon.

I represent the strap as broken, showing but a single bell; but it will be understood

that the strap is made of the required length, and the bells arranged thereon in the usual manner.

The peculiarity of the strap is the serpentine edge, (shown in the illustration,) which, with the bells, produce a pleasing effect.

As an ornamentation, an imitation line of stitches may be run parallel with the edges of the strap, as shown, or parallel to each other; but such additional ornamentation is not essential to the design.

I claim as my invention—

The design for bell-strap, as herein described, and shown in the accompanying illustration.

WILLIAM E. BARTON.
